UNITED STATES PATENT OFFICE

160,364

WIND VANE

Herbert C. Brown, Oklahoma City, Okla.

Application October 13, 1949, Serial No. 5,473

Term of patent 7 years

(Cl. D52—1)

To all whom it may concern:

Be it known that I, Herbert C. Brown, a citizen of the United States, residing at Oklahoma City, in the county of Oklahoma and State of Oklahoma, have invented a new, original, and ornamental Design for a Wind Vane, of which the following is a specification reference being had to the accompanying drawings, forming part thereof.

Figure 1 is a front perspective view of a wind vane showing my new design; and

Figure 2 is a rear perspective view thereof.

I claim:

The ornamental design for a wind vane, as shown.

HERBERT C. BROWN.
